UNITED STATES PATENT OFFICE.

PHILIP T. HANDIGES, OF ST. LOUIS, MISSOURI, ASSIGNOR, BY MESNE ASSIGNMENTS, OF ONE-HALF TO ALBERT WAYCOTT, OF ST. LOUIS, MISSOURI.

CAR-COUPING.

SPECIFICATION forming part of Letters Patent No. 727,133, dated May 5, 1903.

Application filed March 31, 1902. Serial No. 100,661. (No model.)

To all whom it may concern.

Be it known that I, PHILIP T. HANDIGES, a citizen of the United States, residing in the city of St. Louis, in the State of Missouri, have 5 invented certain new and useful Improvements in Car-Couplings, of which the following is a full, clear, and exact description, reference being had to the accompanying drawings, forming part of this specification.

10 My invention relates to means whereby the knuckles of car-couplings are swung upon their pivots upon the lifting of the locking-pin.

The invention consists in features of 15 novelty hereinafter fully described, and pointed out in the claims.

Figure I is a perspective view of my improved coupling. Fig. II is a detail horizontal section taken on line II II, Fig. I. Fig. 20 III is a vertical longitudinal section taken on line III III, Fig. II. Fig. IV is a vertical transverse section taken on line IV IV, Fig. II. Fig. V is a rear view of one of the knuckles. Fig. VI is a perspective view showing 25 the lower end of the locking-pin and the lever by which the knuckle is moved upon the raising of the locking-pin.

1 designates the draw-head of the coupler, and 2 the knuckle, pivotally mounted in the 30 draw-head by means of the pin 3.

4 is the tail of the knuckle, having an inclined face 5 at its lower edge extending downwardly from the end of the tail of the body of the knuckle, as seen in Fig. V.

35 6 designates a locking-pin having a shoulder 7, that is adapted to rest on the tail of the knuckle 2 when the knuckle is swung open. The locking-pin is narrowed from the location of the shoulder 7 downwardly and carries at its lower end a lug 8.

9 is a lever pivoted at 10 to the draw-head 1 interior thereof alongside of the lower portion of the locking-pin 6 and extending across said locking-pin to a point beneath the position occupied by the tail of the knuckle 2 when the knuckle is in closed condition, so that said tail will rest with its inclined face 5 in contact with or in proximity to the free end of said lever. One side of the lever 9 is

45 recessed at 11 to receive the lug 8, carried by the lower end of the locking-pin 6, and be-

tween the location of the recess and the free end of the lever is a cam 12, beneath which the lug 8 rides as it traverses the lower surface of the lever on being raised to disengage 55 the tail of the knuckle 2. This cam is applied to the lever for the purpose of providing a more sudden actuation of the lever by the locking-pin as the lever approaches the end of its travel at the rear of the tail of the 60 knuckle, against which it presses as the locking-pin is raised, thereby accelerating the movement of the knuckle as it approaches the conclusion of its opening movement, and a more direct pressure is obtained against the 65 rear of the tail of the knuckle.

It will be seen from the foregoing that the lever 9 is so positioned beneath the tail of the knuckle of the coupling as to bear against the inclined face 5 at the lower side thereof, 70 so that upon the lifting of the locking-pin 6 the lug 8 at the lower end of said pin acts upon the lever and causes the lever in turn to press against the inclined face of the knuckle-tail, against which it rides and operates 75 to swing the tail outwardly as the locking-pin is raised to free it from restraint. The locking-pin may be raised by any suitable means, such as the rocking-rod 13, carried by the car and provided with an arm 14, that is connected to the pin.

I claim as my invention—

1. In a car-coupling, the combination with a coupling-head, and a knuckle, the latter having a rearwardly-projecting tail, an inclined lower face or edge, of a locking pin or block and a pivoted lever projecting under the inclined edge of the knuckle-tail, the said lever being actuated by the movements of the pin or block. 85

2. In a car-coupling, the combination with a coupling-head and a knuckle, the latter having a tail provided with a rearwardly and upwardly inclined lower face or edge, of a locking pin or block and a pivoted lever, the latter adapted to be moved into contact with the inclined face or edge of the knuckle by said pin or block. 95

3. In a car-coupling, the combination with a coupling-head and a knuckle, the latter having a tail provided with a rearwardly and upwardly inclined lower face or edge, of a 100

- locking pin or block having a cut-away portion to permit of the passage of the knuckle-tail, and a pivoted lever to engage the lower inclined face or edge of said tail, the said lever being actuated by the pin or block.
4. In a car-coupling, the combination with a coupling-head and a knuckle, the latter having a tail provided with a rearwardly and upwardly inclined lower face or edge, of a locking pin or block having a cut-away portion and a projection below said cut-away portion and a knuckle-throwing lever pivoted to the coupling-head and resting over the projection on the pin or coupling.
5. In a car-coupling, the combination with a draw-head provided with a locking-pin aperture, of a knuckle pivotally mounted in said draw-head and having an inclined face at the lower side of its tail, a lever pivoted to said draw-head at one side of the locking-pin aperture and extending across said aperture to the inclined face of the knuckle-tail, and a locking-pin arranged to engage said lever for the purpose of causing it to move said knuckle, substantially as described.
6. In a car-coupling, the combination of a draw-head, a knuckle pivotally mounted in said draw-head and having a tail provided with an inclined lower face, a locking-pin, a lug carried by said locking-pin at its lower end, and a lever pivoted to said draw-head and extending across said locking-pin, said lever having its lower end adapted to occupy a position beneath the inclined face of said knuckle-tail and being adapted to receive the engagement of the lug carried by said locking-pin, substantially as and for the purpose set forth.
7. In a car-coupling, the combination of a draw-head, a knuckle pivotally mounted in said draw-head and having a tail provided with an inclined face at its lower side, a locking-pin positioned in said draw-head, a lever pivoted to said draw-head and having its free end adapted to occupy a position beneath the inclined face of said knuckle-tail, and a cam carried by said lift-lever adapted to receive the stud carried by said locking-pin, substantially as described.
8. In a car-coupling, the combination with a draw-head provided with a locking-pin aperture, of a knuckle pivotally mounted in said draw-head, a lever pivoted to said draw-head at one side of the locking-pin aperture and extending across said aperture to the tail of the knuckle, and a locking-pin located in said aperture and adapted to engage said lever for the purpose of causing the lever to move said knuckle and throw it open, substantially as set forth.
- In testimony whereof I have hereunto set my hand this 27th day of March, 1902.
- PHILIP T. HANDIGES.
